(57) **CLAIM**

The ornamental design for an electric dental water jet, as shown and described.

DESCRIPTION

FIG. 1 is a front perspective view of an electric dental water jet showing my new design;

FIG. 2 is a rear perspective view thereof;

FIG. 3 is an enlarged bottom plan view thereof;

FIG. 4 is an enlarged top plan view thereof;

FIG. 5 is a front elevational view thereof;

FIG. 6 is a right side elevational view;

FIG. 7 is a rear elevational view thereof; and,

FIG. 8 is a left side elevational view thereof.

The broken lines shown in the drawings represent portions of the electric dental water jet that form no part of the claimed design.
